ABSTRACT

A new and distinct variety of *Phalaenopsis* plant named 'PHALGIPCOL', particularly characterized by having large white flowers with greenish-yellow and white lips, 1 to 2 peduncles that are long and sturdy, leaves that are oblong, and is propagated by meristem tissue culture, is disclosed.

3 Drawing Sheets

1

Genus and species: *Phalaenopsis* hybrid.
Variety denomination: 'PHALGIPCOL'.

BACKGROUND OF THE NEW PLANT

The present invention relates to a new and distinct cultivar of *Phalaenopsis* plant, botanically known as *Phalaenopsis* hybrid of the Orchidaceae family, commonly referred to as moth orchid, and hereinafter referred to by the variety name 'PHALGIPCOL'.

The new *Phalaenopsis* plant is a product of a planned breeding program conducted by the inventor in Bleiswijk, the Netherlands. The objective of this breeding program was to create a new *Phalaenopsis* plant with numerous attractive large white flowers with greenish-yellow and white lips, suitable for potted plant production.

The new *Phalaenopsis* plant 'PHALGIPCOL' is a result of cross-pollination made by the inventor in January 2009 in Bleiswijk, the Netherlands, of the proprietary female, or seed parent, *Phalaenopsis* hybrid '01-1958' (unpatented) with the proprietary male, or pollen parent, *Phalaenopsis* hybrid '6541-01' (unpatented).

The new *Phalaenopsis* was selected by the inventor as a single plant within the progeny of the stated cross-pollination in a controlled greenhouse in Bleiswijk, the Netherlands, in May 2012. Asexual reproduction of the new *Phalaenopsis* plant by meristem tissue culture since 2015 in Bleiswijk, the Netherlands, has demonstrated that the new variety reproduces true to type with all of the characteristics, as herein described, firmly fixed and retained through successive generations.

Plant Breeder's Rights for this variety have been applied for in the European Union on Sep. 25, 2018, by Applicant who obtained the subject matter disclosed directly from the Inventor. 'PHALGIPCOL' has not been made publicly available or sold anywhere in the world more than one year prior to the effective filing date of this application.

SUMMARY OF THE INVENTION

The following are the most outstanding and distinguishing characteristics of this new cultivar when grown under

2

normal horticultural practices in Bleiswijk, the Netherlands, and can be used to distinguish 'PHALGIPCOL' as a new and distinct variety of *Phalaenopsis* plant:

- 1) Large white flowers with greenish-yellow and white lips;
- 2) 1 to 2 peduncles;
- 3) Peduncle is long and sturdy; and
- 4) Shape of the leaf is oblong.

DESCRIPTION OF THE PHOTOGRAPHS

This new *Phalaenopsis* plant is illustrated by the accompanying photographs which show the overall plant habit including blooms, buds, and foliage of the plant; the colors shown are as true as can be reasonably obtained by conventional photographic procedures. The photographs were taken in a greenhouse in Bleiswijk, the Netherlands, from 50-week-old plants in April 2019. Colors in the photographs may differ from the color values cited in the detailed botanical description, which accurately describe the actual colors of the new variety.

FIG. 1 shows the overall plant habit, including blooms, buds, and foliage of 'PHALGIPCOL'.

FIG. 2 shows a close-up of a flower of 'PHALGIPCOL'.

FIG. 3 shows an overhead view of the leaves of 'PHALGIPCOL'.

DESCRIPTION OF THE NEW VARIETY

The following detailed description sets forth the distinctive characteristics of 'PHALGIPCOL'. Plants of the new *Phalaenopsis* have not been observed under all possible environmental conditions. The phenotype may vary somewhat with variations in environment such as temperature, light intensity and day length, without, however, any variance in genotype. The chart used in the identification of colors described herein is The R.H.S. Colour Chart of The Royal Horticultural Society, London, England, 2015 edition,

except where general color terms of ordinary significance are used. The color values were determined under 4000-6000 lux natural light in a greenhouse in Bleiswijk, the Netherlands. Observations and measurements were made in April 2019 on flowering plants which were planted in 12-centimeter (diameter) pots. After in-vitro propagation, the plants were grown in nursery trays for 20-24 weeks, followed by transplantation to 12-centimeter pots and grown in a greenhouse between 27° C. to 29° C. for 30 weeks, continued by a cooling period of 8 weeks between 18° C. to 20° C. and 12 weeks in a greenhouse of 21° C. Flowering occurs after 50 weeks in 12-centimeter pots.

DETAILED BOTANICAL DESCRIPTION

5

Classification:

Family.—Orchidaceae.*Botanical*.—*Phalaenopsis* hybrid.*Common name*.—Moth orchid.*Variety name*.—‘PHALGIPCOL’.

15

Parentage:

Female parent.—*Phalaenopsis* cultivar ‘01-1958’ (un-patented).*Male parent*.—*Phalaenopsis* cultivar ‘6541-01’ (un-patented).

20

Propagation:

Type.—Meristem tissue culture.

Roots:

Root description.—Greyed-green (between RHS 190B and 190C) colored roots with branching lateral roots having light yellow-green (RHS 145B) colored root tips.

30

Plant:

Commercial crop time to flowering.—Following asexual propagation (in-vitro), the rooted cuttings grow for 20-24 weeks. After transplantation into 12-cm pots, the plants are finished after 48 to 50 weeks.

35

Growth habit of peduncle.—Upright to slightly pendant with raceme inflorescence.

40

Height (from soil level to top of inflorescence).—Approximately 68.0 cm to 73.0 cm.*Width (measured from leaf tips)*.—About 45.0 cm to 47.0 cm.

45

Vigor.—Sturdy.

Leaves:

Mature leaves.—Quantity per plant: 8 to 10 leaves are produced before flowering. Length (fully expanded): 22.0 cm to 24.0 cm. Width: 8.0 cm to 9.0 cm. Shape: Oblong. Base shape: Moderately elongated. Apex: Obtuse unequal. Leaf blade angle with the petiole (measured from the horizontal position): Between 20 degrees and 30 degrees. Leaf margin: Entire. Color: Upper surface: RHS 146A. Lower surface: RHS 146B. Texture (both upper and lower surfaces): Rough. Thickness: 2.0 mm to 3.0 mm. Variegation: Absent. Venation: Pattern: Parallel. Color of the midvein: Upper surface: RHS 146A. Lower surface: RHS 145B.

55

Peduncle:

Quantity per plant.—1 to 2.*Number of flowers per peduncle*.—7 to 12.*Length*.—68.0 cm to 73.0 cm.*Diameter*.—7.0 mm to 8.0 mm.*Strength*.—Strong.

60

65

Aspect.—Upright to slightly pendant.*Texture*.—Smooth.*Color*.—Mix of brown (RHS N200A) and green (RHS 146C).*Internode length*.—5.0 cm to 7.0 cm.

Inflorescence description:

Appearance.—Upright to slightly pendant, raceme inflorescence with bilaterally symmetrical flowers that open in succession beginning with the lower-most flower.*Number of inflorescences*.—1 to 2.*Inflorescence size*.—Height (from base to tip): 260.0 mm to 310.0 mm.*Flowering time*.—First flowers can be expected 10 to 11 months after planting in a 12-cm pot.*Flower*.—Height: 93.0 mm to 98.0 mm. Diameter: 110.0 mm to 115.0 mm. Depth of lip: 24.0 mm to 26.0 mm.*Flower longevity*.—On the plant: 18 to 24 weeks.*Fragrance*.—Absent.*Flower bud*.—Average size: Large. Length: 30.0 mm to 32.0 mm. Width: 24.0 mm to 26.0 mm. Shape: Egg shaped. Color: Light yellow-green (RHS 145C) with a touch of light reddish-purple (RHS N78D).*Petals*.—Arrangement: Open/free. Shape: Semi-circular. Apex: Rounded asymmetric. Margin: Slightly undulated. Length (from base to tip): 50.0 mm to 52.0 mm. Width: 67.0 mm to 69.0 mm. Position of the broadest part of the petal: Toward the base. Color (when fully opened): Upper surface: Basic color: White (RHS NN155C). Over color: Absent. Lower surface: Basic color: White (RHS NN155C). Over color: Absent.*Dorsal sepal*.—Shape: Elliptic. Apex: Obtuse symmetric. Margin: Entire. Length (from base to tip): 52.0 mm to 54.0 mm. Width: 37.0 mm to 39.0 mm. Color (when fully opened): Upper surface: Basic color: White (RHS NN155C). Over color: Absent. Lower surface: Basic color: White (RHS NN155C). Over color: Very light purple (RHS 76B).*Lateral sepals*.—Shape: Ovate. Apex: Obtuse asymmetric. Margin: Entire. Length (from base to tip): 55.0 mm to 57.0 mm. Width: 35.0 mm to 37.0 mm. Color (when fully opened): Upper surface: Basic color: White (RHS NN155C). Over color: Slightly light yellow-green (RHS 145C) at the base. Lower surface: Basic color: White (RHS NN155C). Over color: Light yellow-green (RHS 145D) at the base and very light purple (RHS 76B) toward the tip with light reddish-purple midvein (RHS N78D) toward the tip.*Labelum (lip)*.—Whiskers: Present. Length of whiskers: 30.0 mm to 32.0 mm. Color of whiskers: Greenish-Yellow (RHS 6A). Pubescence on the lip: Absent.*Lateral lobe*.—Shape: Type V (as described in the International Union for the Protection of New Varieties of Plants (UPOV) Test Guidelines for *Phalaenopsis*); spatulate. Margin: Undulated. Length: 23.0 mm to 25.0 mm. Width: 17.0 mm to 19.0 mm. Color: Red stripes (RHS 184A and 182B) at the base; greenish-yellow (RHS 6A) on one side; white (RHS NN155C) toward other side.*Apical lobe*.—Shape: Triangular. Margin: Entire. Length: 21.0 mm to 23.0 mm. Width: 27.0 mm to

29.0 mm. Color: Greenish-yellow (mix of RHS 6A and 153D) at the base and slightly reddish-orange (RHS 176C); white (RHS NN155C) toward whiskers.

Callus.—Average size: Large. Height: 7.0 mm to 8.0 mm. Length: 7.0 mm to 8.0 mm. Width: 4.0 mm to 5.0 mm. Color: Yellow (RHS 9A); dotted (RHS 175B).

Reproductive organs:

Column.—Length: 9.0 mm to 11.0 mm. Diameter: 6.0 mm to 7.0 mm. Color: White (RHS NN155C).

Pollinia.—Quantity: 2. Diameter: 0.9 mm to 1.1 mm. Color: Orange (RHS 24A).

Ovary.—Length: 10.0 mm to 12.0 mm. Diameter: 3.0 mm to 3.3 mm. Color: Light purple (RHS 84C) toward the flower.

Pedicel.—Length: 38.0 mm to 40.0 mm. Diameter: 3.4 mm to 3.7 mm. Color: Light yellow-green (RHS 145B to 145C) at the base; light purple (RHS 84C) toward the flower.

Disease, pest, and stress resistance: No specific resistance or susceptibility observed to pathogens and pests common to *Phalaenopsis* to date.

Fruit and seeds: Fruit and seed development has not been observed on plants of the new *Phalaenopsis* to date.

COMPARISON WITH PARENTAL LINES AND MOST SIMILAR VARIETIES

‘PHALGIPCOL’ differs from female parent plant ‘01-1958’ (unpatented) in that ‘PHALGIPCOL’ has obtuse dor-

sal sepal apexes and petals that are open/free, whereas ‘01-1958’ has slightly emarginated dorsal sepal apexes and petals that are touching.

‘PHALGIPCOL’ differs from male parent plant ‘6541-01’ (unpatented) in that ‘PHALGIPCOL’ has obtuse dorsal sepal apexes and greenish-yellow whiskers, whereas ‘6541-01’ has rounded to slightly emarginated dorsal sepal apexes and white whiskers with yellow tips. Additionally, ‘PHALGIPCOL’ has larger flowers than ‘6541-01’.

‘PHALGIPCOL’ is most similar to the commercial *Phalaenopsis* plants named ‘PHALFMACON’ (U.S. Plant Pat. No. 29,614) and ‘PHALFOREI’ (U.S. Plant Pat. No. 28,944). ‘PHALGIPCOL’ differs from the commercial variety ‘PHALFMACON’ in that ‘PHALGIPCOL’ has greenish-yellow whiskers and a very light purple (RHS 76B) overcolor on the lower surface of the dorsal sepals, whereas ‘PHALFMACON’ has yellow whiskers with yellow-orange tips and a diluted light reddish-purple (RHS N78D) overcolor on the lower surface of the dorsal sepals. Additionally, ‘PHALGIPCOL’ has longer leaves than ‘PHALFMACON’.

‘PHALGIPCOL’ differs from the commercial variety ‘PHALFOREI’ in that ‘PHALGIPCOL’ has a very light purple overcolor on the lower surface of the dorsal sepals, whereas ‘PHALFOREI’ has no overcolor on the lower surface of the dorsal sepals. Additionally, ‘PHALGIPCOL’ has longer leaves, larger flowers, and longer whiskers than ‘PHALFOREI’.

I claim:

1. A new and distinct variety of *Phalaenopsis* plant named ‘PHALGIPCOL’, substantially as described and illustrated herein.
